UNITED STATES PATENT OFFICE.

EUGENE SMITH, OF PHILADELPHIA, PENNSYLVANIA, ASSIGNOR, BY MESNE ASSIGNMENTS, TO BRIDGET CONWAY HOWARD, OF PHILADELPHIA, PENNSYLVANIA.

BOOT AND SHOE SEWING MACHINE.

1,175,877.

Specification of Letters Patent. Patented Mar. 14, 1916.

Application filed October 17, 1910. Serial No. 587,554.

To all whom it may concern:

Be it known that I, EUGENE SMITH, a citizen of the United States, residing at Philadelphia, in the county of Philadelphia and 5 State of Pennsylvania, have invented a certain new and useful Improvement in Boot and Shoe Sewing Machines, of which the following is a specification.

My invention relates to a new and useful 10 improvement in boot and shoe sewing machines, and has for its object to so construct a machine of this description as to so hold the work as to provide for the formation of a stitch closer to the top of a shoe than has 15 heretofore been possible and to produce a lock stitch.

A further object of my invention is to provide for positively holding the work, feeding it a predetermined distance lengthwise, locking said work in the position to 20 which it has previously been fed, taking a fresh hold upon the work prior to the insertion of the awl of the formation of the stitch.

25 A still further object of my invention is to provide for a positive hold on the thread, back of the take-up, at predetermined times, so that when the thread is drawn by the take-up, the slack formed therein by its 30 passage around the shuttle, will be entirely taken up and the thread drawn tight.

With these ends in view, this invention consists in the details of construction and combination of elements hereinafter set 35 forth and then specifically designated by the claims.

In order that those skilled in the art to which this invention appertains may understand how to make and use the same, I will 40 describe its construction in detail, referring by letter to the accompanying drawing forming a part of this specification, in which—

Figure 1 is a side elevation of the machine, showing the feed dog in the position 45 which it assumes, when locking the work just prior to feeding. Fig. 2, is an elevation taken from the opposite side of the machine. Fig. 3, a front elevation. Fig. 4, a plan 50 view. Fig. 5, a detail perspective of the feed mechanism, take up, shuttle and cam mechanism for operating the same. Fig. 6, a detail side elevation of the locking dog, and the cam mechanism for operating the

same. Fig. 7, a front elevation thereof. Fig. 8, a detail side elevation of the thread carrier, and the operating mechanism therefor. Fig. 9, a front view of the same. Fig. 10, a diagram of the needle and awl, showing their relative position and shape. Fig. 11 a detail perspective of one form of work rest. Fig. 12, a similar view of a slightly modified form of work rest. Fig. 13, a sectional perspective of the wax pot and pump. Fig. 14, a section at the line X—X of Fig. 13. Fig. 15, is a section at the line X—X of Fig. 3, showing the hollow spindle, awl and needle carrier, and pinion for operating the same.

In carrying out my invention as here embodied, 1 represents the frame of the machine, which may be of any suitable design, to support the various operating parts. Journaled in this frame is a short hollow spindle 2, to which is secured the awl and 75 needle carrier 3, while to the opposite end of this hollow spindle is secured the pinion 4, which meshes with the segmental gear 5, by which the pinion is oscillated first in one direction and then the other for the purpose 80 hereinafter set forth.

6 represents the awl which is detachably secured to the carrier 3 and this awl is so curved as to form a part of a circle, the center of which is the center of rotation of 85 the carrier. To the opposite side of the carrier is also detachably secured the needle 7, which is likewise so curved as to form a part of the same circle as that of the awl, the hook end of this needle is of the shape 90 shown in Fig. 10, which will cause the thread when engaged therewith to be drawn on the line coinciding with the hole formed by the awl.

8 represents the work rest, which when of 95 the construction shown in Fig. 11, is utilized for stitching the sole to the welt, and when of the construction shown in Fig. 12 is utilized for seaming or stitching the welt on to the upper and insole, and this rest has 100 formed therewith, a dovetail shank 9, adapted to fit on a corresponding dovetail groove formed with the frame and be held in place by the screws 10. In the rest is formed an elongated slot 11 for the passage of the 105 needle and awl and to facilitate the feeding of the work as hereinafter set forth.

12 is a cam shaft pivoted in suitable bear-

ings upon the frame and upon this shaft is secured the cam disk 13 in which is formed the cam groove 14.

The lever 15 is pivoted at 16 and carries the stud 17 which projects in the cam groove 14, by which this lever receives its reciprocating motion which latter is transmitted through the connecting rod 18, to the segmental gear 5, to bring about the oscillations of the awl and needle as before set forth.

A sliding shaft 19 passes through the hollow spindle 2 and has a further bearing in the bracket 20 and on this sliding shaft 15 is secured the feed dog lever 21, the upper end of which is adjustably attached to the connecting rod 22, by being pivoted upon the pin 22^a set in the block 22^b fitted to slide in the slot formed in said connecting rod 20 and the position of this block is regulated by the screw 22^c. The feed dog lever is adapted to slide upon the pin 22^a in order that it may follow the movements of the shaft 19 to which it is secured. The object 25 of this adjustment is to determine the depth to which the feed dog penetrates the work and to provide for handling various thicknesses of work.

The connecting rod 22 is pivoted to the cam lever 23, the latter being pivoted to the frame at 24 and is provided with a stud 25 which projects in the cam groove 26 formed in the cam disk 13 on the opposite side of the cam groove 14, and this cam groove is of such contour as to properly time the oscillating movements of the feed dog lever.

The feed dog lever has formed therewith or secured thereon the feed dog 27 which is 40 in the shape of a pointed prong adapted to penetrate the work to a considerable depth and if necessary pass entirely through the same, thus taking a firm and positive hold thereon in order that the work may not slip 45 or be displaced when being fed step by step for determining the length of the stitches.

In order that the feed dog may be given a sidewise movement in addition to the oscillating movement just described, the block 50 28 is set upon the outer end of the sliding shaft 19 between the two collars 29, and this block has projecting therefrom the pins 30 adapted to engage the slots in the forked end of the stitch regulating lever 31, and 55 this lever has an elongated slot 32 formed therein through which the set bolt 33 passes, the lower end of which is held in a groove in the frame, the upper end being provided with the thumb nut 34. By adjusting this 60 thumb nut lengthwise of the slot 32 it is obvious that the throw of the outer end of the lever will be varied as the stud forms the fulcrum of said lever.

35 is a bracket projecting upward from the frame having a slot formed in its over-

hanging end, and in this slot projects the upper end of the pin 36, set in the rear end of the stitch regulating lever 31, while the lower end of this pin projects in the cam groove 37, formed in the cam disk 38, said 70 disk being secured upon the power shaft 12. By this arrangement the feed regulating lever will be held against displacement when the bolt 33 is being adjusted to vary the length of the stitch and at the same time 75 the heel end of this lever will be free to oscillate sidewise from the action of its cam groove.

By this arrangement of cams and levers the feed dog will be caused to pierce the 80 work, feed it sidewise, release said work, move in the opposite direction and take a fresh hold thereon. During these operations of the feed dog it is essential that the work be alternately held by the secondary 85 mechanism and this is accomplished by the presser foot 39, which is attached to and formed with the lever 40 pivoted upon the hollow spindle 2 and consequently concentrically with the awl and needle carrier. 90

The upper end of the lever 40 is slotted at 41, by which slot it is pivoted to the inner end of the cam lever 42, the latter carrying the roll 43 adapted to be operated upon by the cam surface 44 on the cam disk 13, and this lever is secured in its normal position, as shown in Fig. 6 by the spring 45, the cam surface 44 being so timed as to swing the presser foot 39 out of engagement with the work just prior to the feeding of said work by the feed dog, and just prior to the disengagement of the feed dog from the work the presser foot again enters into engagement therewith, holding it in this position until the feed dog is moved backward 105 and again engages the work.

In order that the work may be released when desired, a handle 46 projects upward from the cam lever 42 and by drawing forward upon this handle against the action of the spring 45 the presser dog will be 110 swung outward.

47 represents the take up lever which is pivoted to the frame 48 and has a stud 49 shown in dotted lines in Fig. 2, which stud 115 projects into the cam grooves 50, on the inner face of the cam disk 38, giving this lever a long swinging movement. To the upper end of the lever is adjustably attached the tension disks 51, between which the thread 52 passes on its way to the needle. In order that the thread may be firmly held when the take up lever is drawing the slack from around the shuttle and tightening the 120 stitch, I provide a clamp 53 which is pivoted at 54 and is attached to and closed against the stationary jaw 55, between which the thread passes and thus clamp the thread at 125 a predetermined time, and the action of this clamp is brought on by the roll 56 traveling 130

upon the periphery upon the cam disk 58, which is so formed as to permit the release of the thread at the proper time when it is being drawn forward by the needle and again clamp the same when the take up is taking up the slack. The thread when leaving the clamp may pass over or around any suitable tension disk, and through any suitable guides and finally pass through a loop 10 in the tension spring 59 and down through an eye in the looper 60 which latter is secured to the bar 61 which is operated by the cam lever 62 and the roll 63, which travels upon the periphery of the cam disk 13, the latter having a suitable cam surface 64 thereon for actuating this cam lever and giving the bar a to and fro sliding movement and consequently carrying the thread which is passed through the eye into and 20 out of the path of the needle.

65 represents the shuttle holder which consists of two spring rings, secured to the base 66, which latter is adjustably held upon the bracket 67 by the set screw 68. 25 The shuttle 69 is set between these spring rings the edges of the latter being cut away so as to make reduced bearing surfaces as indicated at 95 and thus reduce the friction.

In order that the thread from the needle 30 may be looped around the shuttle, I provide the hook 70 which is carried by the disk 71 secured upon the shaft 72, upon the opposite end of which is secured the pinion 73, meshing with the rack 74.

35 The rack 74 is carried by the outer end of the cam lever 75, which is pivoted at 76 and is provided with a stud 77, which projects into the cam groove 78 formed in the cam disk 38, the stud and cam groove being shown 40 in dotted lines in Fig. 2, thus the looper will be caused to oscillate in proper time to draw the thread from the needle and loop it around the shuttle.

In sewing machines it is very essential to 45 apply wax to the thread prior to its being used for the formation of the stitches, and heretofore this has been usually accomplished by drawing the thread through a wax pot, back to the machine, the result being that when the machine is stopped temporarily the wax would be chilled, and before the machine could again be used it was necessary to draw off the previously waxed thread, but I overcome this objection by 55 providing a water jacket wax pot 79, which may be held over the gas burner 80 in any suitable manner, and within this pot is secured the pump barrel 81, the lower end of which is threaded through the bottom of 60 the inner casing of the wax pot and into the outer casing as clearly shown in Fig. 15, and in this pump barrel is fitted the plunger 82.

83 is a cam lever in the outer end of which is swiveled the adjusting screw 84 which 65 latter is threaded into the plunger 82, so

that manipulating this screw the actual position of the plunger within the pump barrel will be adjusted.

Holes 85 are formed through the pump barrel on a level with the bottom of the inner casing of the wax pot, so that when the plunger is moved upward, a certain amount of wax will be drawn from the pot in said barrel and when the plunger is moved downward it will first eject the surplus wax from 75 the barrel until its lower edge passes the holes 85 after which it will force the wax through the tube 86; the under side of the plunger being hollowed to facilitate its action. 80

The wax tube 86 leads to a point just back of the work rest and has a groove 87 formed in its inner end in alinement with the travel of the needle and awl, and as the wax is forced through this tube it will issue into 85 this groove through which the thread is drawn and consequently the wax will be applied to the thread at the proper point, namely, at the work.

The cam lever 83 which operates the plunger and the wax pot is pivoted at 90 and carries the roll 89, which rides upon the periphery of the cam disk 38, the contour of which is such as to operate this lever at predetermined times for feeding the wax at the 95 proper time.

Power may be applied to the machine in any suitable manner, such as by a belt wheel 88, secured to the shaft 12.

From the foregoing description it is obvious that as the awl and needle are both upon the same carrier and curve to the same circle, the needle must always follow in the hole made by the awl, and thus relieve it of any strain in piercing the work. The feed 100 dog being in the shape of a prong, will penetrate the work to such an extent that when the awl strikes the same hole less resistance will be offered said awl, and the sidewise movements of the feed dog are so timed that 110 the indenture made thereby will be brought into alinement with the movement of the awl, thus distributing the work of piercing the leather so that any thickness of leather may be sewed without undue strain upon 115 the feed dog or the needle.

Of course I do not wish to be limited to the exact details of construction here shown, as these may be varied within wide limits without departing from the spirit of my invention. 120

As shown in Fig. 10 the end of the needle is beveled at *a* so as to bring its point flush with its outside circumference to facilitate stitching close to the body of the shoe, and the awl is likewise beveled as indicated at *b* for the same purpose. 125

Having thus fully described my invention, what I claim as new and useful, is:— 130

1. In a shoe sewing machine, the combi-

4
nation of a suitable frame, a carrier, means for oscillating said carrier first in one direction and then in the other, an awl attached to the carrier, said awl curved so as to form 5 a part of a circle, the center of which is the center of rotation of the carrier, a needle curved in the same manner as the awl and also attached to the carrier, a work rest having an opening therein, a presser foot 10 adapted to clamp the work against said rest, and release the same at predetermined times, a feed dog adapted to penetrate the work and feed it sidewise step by step when the presser foot is withdrawn from said work, 15 means for bringing about this movement, and a circular shuttle for carrying the bobbin, as specified.

2. In a machine of the character described, a combined awl and needle carrier, 20 a spindle upon which said carrier is secured, a pinion secured upon the opposite end of said spindle, a segmental gear meshing with the pinion for oscillating the same first in one direction for driving the awl 25 through the work and then the other for passing the needle through the hole thus formed by said awl, a cam mechanism actuating the segmental gear, a curved awl secured to one end of the carrier, a curved 30 needle secured to the opposite end of the carrier, the line of the curve of said awl and needle being in the same circle and plane, a work rest having an opening therein, a feed dog lever, a sliding shaft, to which said 35 lever is secured, said shaft being journaled in the spindle to which the awl and needle carrier is secured, means for sliding said shaft and consequently the feed dog lever longitudinally, means for swinging said feed 40 dog lever, and a prong shaped feed dog attached to the lever and adapted to penetrate the work so as to assist the awl in forming a hole through said work for the 45 passage of the needle, as specified.

3. In a machine of the character described, a needle carrier, a spindle upon which said carrier is secured, means for oscillating the same first in one direction and then the other, a curved awl secured to 50 one end of the carrier, a curved needle secured to the opposite end of the carrier, a work rest having an elongated opening therein, a presser foot means for oscillating the same, a feed dog lever, a sliding shaft to which said lever is secured, said shaft being journaled concentrically with the awl and needle and in the spindle of the carrier of said awl and needle, means for sliding the shaft and consequently the feed dog 55 lever longitudinally, means for swinging said feed dog lever, a prong shaped feed dog attached to the lever and adapted to penetrate the work so as to assist the awl in 60

forming a hole through said work for the 65 passage of the thread, a thread carrier having an eye therethrough for the passage of the thread, and means for moving said carrier to and away from the path of the needle whereby the hooked end of the needle will be caused to engage said thread, as 70 specified.

4. In a shoe sewing machine, the combination of a feed dog adapted to form a preliminary opening in the work for an awl, a 75 presser foot and an awl and needle, with mechanisms for operating said elements, said mechanisms being so timed as to put the presser foot in contact with the work while the feed dog is out of contact therewith and the awl and needle are operating on said work, and to take the presser foot out of contact with the work while the feed dog is in contact therewith, as and for the purpose set forth.

5. In a device of the character stated the 85 combination of a work rest, an awl, a needle, a presser foot arranged to engage the work at predetermined intervals, and a feed dog arranged to engage the work alternately with the presser foot and adapted to form a 90 preliminary opening in the work for the awl.

6. In a device of the character stated the combination of a work rest, an awl, a needle, a presser foot arranged to engage the work at predetermined intervals, and a feed dog 95 arranged to engage the work before the presser foot is disengaged therefrom to advance the work and form an indent in the work for the awl.

7. In a device of the character stated the 100 combination of a work rest, an awl, a needle, a presser foot arranged to engage the work at predetermined intervals, and a prong shaped feed dog adapted to penetrate the work at predetermined intervals and at pre- 105 determined distances, whereby a preliminary opening is formed in the work for the awl to decrease the resistance to said awl.

8. In a device of the character stated the combination of a work rest, an awl, a needle, a presser foot arranged to engage the work, at predetermined intervals, a prong shaped feed dog adapted to penetrate the work to 110 form a preliminary opening for the awl, means for causing said feed dog to engage the work at predetermined intervals, and means for advancing the work a predetermined distance to cause the awl to enter the 115 preliminary opening made by the feed dog.

In testimony whereof, I have hereunto 120 affixed my signature in the presence of two subscribing witnesses.

EUGENE SMITH.
